UNITED STATES PATENT OFFICE

HORACE B. LONG, OF WORCESTER, AND ERWIN L. HILL, OF WEST UPTON,
MASSACHUSETTS; SAID LONG ASSIGNOR TO SAID HILL.

MILK-AERATOR.

SPECIFICATION forming part of Letters Patent No. 323,347, dated July 28, 1885.

Application filed March 14, 1885. (No model.)

To all whom it may concern:

Be it known that we, HORACE B. LONG, of Worcester, and ERWIN L. HILL, of West Upton, in the county of Worcester and State 5 of Massachusetts, have invented an Improvement in Milk-Aerators, of which the following is a specification.

The object of our invention is to provide an apparatus by means of which a uniform 10 current of air may be forced into and through the milk, for cooling the same and driving off the obnoxious odors, and also to furnish an air-delivering rose or nozzle, the interior of 15 which is made readily accessible for the purpose of cleaning; and our invention consists in the combination of the rose or nozzle, with two oppositely-moving bellows and a bellows-chamber, and also in the construction of the 20 rose or nozzle in hinged sections, as herein-after set forth.

Figure 1 is a central vertical section of the bellows portion of the apparatus, the milk-can under the machine being broken away in 25 order to show our improved rose or nozzle in elevation. Fig. 2 is a vertical section taken principally in the line $x-x$ of Fig. 1, the milk-can under the machine being shown in elevation. Fig. 3 is a perspective view of the rose or nozzle as opened for the purpose of 30 cleaning.

In the accompanying drawings, A is the box which serves to inclose and cover the bellows, and B B the legs, which are preferably made of sufficient length to allow the insertion of the milk-can C under the box A, as shown in 35 Figs. 1 and 2. To the bottom a within the box A is secured the standard b , to the upper portion of which is pivoted the hand-lever c , passing outward through a slot made in the 40 side d of the box. At the under side of the bottom a are secured the oppositely moving bellows $e e$, which are operatively connected to the hand-lever c by means of the connecting- 45 rods $f f$.

The bottom board, a , is provided with the two valved-openings $g g$, through which the air drawn into the bellows $e e$ will be forced

into the bellows-chamber h , located at the upper side of the bottom board a , within the box, and centrally of the bottom board is secured the downwardly-directed eduction-tube i through which the air can pass to the attached flexible tube j , and thence to the upwardly-perforated rose or nozzle D, which consists, essentially, of the tube o , the perforated hollow-formed plate k , attached to the tube o , and the covering-plate l , which is hinged to the plate k at the point m , and also provided with a rim, p , which is adapted to inclose the boundary edge of the plate k . A 55 snap-catch, n , is also attached to either of the plates k or l , and serves to hold the plates firmly together when in use, thus causing the air from the bellows to issue from the perforations s of the plate k in small jets, and to 60 pass upward through the milk in the can C, thus cooling and aerating the same and at the same time removing all obnoxious odors.

The plates k and l being hinged to each other the inner face of the plates will be rendered 70 readily accessible for the purpose of cleaning the same, which is a very essential matter in a milk-aerating apparatus.

By means of the bellows-chamber h a uniform continuous stream of air will be forced 75 through the perforations of the rose or nozzle upon the proper up-and-down movement of the hand-lever c .

We claim as our invention—

1. The combination of the hand-lever c , the 80 oppositely-moving bellows $e e$, the receiving bellows-chamber h , flexible tube j , perforated conical plate k , and hinged covering plate l , all arranged and operating substantially as described.

2. The milk aerating rose or nozzle, consisting of the tube o , perforated conical plate k , and covering-plate l , hinged to the plate k , substantially as and for the purpose specified.

HORACE B. LONG.
ERWIN L. HILL.
